POWER RELAY

Otho D. Grandstaff, Chicago, Ill., assignor to Associated Electric Laboratories, Inc., Chicago, Ill., a corporation of Delaware

Application February 6, 1937, Serial No. 124,420

1 Claim. (Cl. 200—87)

This invention relates to improvements in power relays intended primarily for use on alternating current circuits and adapted for the remote control of various line circuits and the like where it is desired to make and break circuits having currents of considerable magnitude passing therethrough. The power relay of the present invention is of the magnetic type and is capable of being operated by either direct or alternating current for the purpose of closing circuits, such as the circuits to battery chargers and battery eliminators or the like, although it may have other uses.

The principal object of the invention is to provide an improved magnetic relay of simple, compact construction which may be manufactured with ease and economy and which will be efficient in use. A further object of the invention is to provide an improved relay comprising improved means for mounting the magnetizable core and the armature which is actuated when the core is energized. Another object is to provide a magnetic relay having a core and an armature in combination with means for regulating the magnetic field which must be applied to the armature to actuate it. Still another object of the invention is to provide an improved power relay having improved means for controlling the intensity and time relation of the magnetic field in different parts of the core for the purpose of permitting the device to be employed efficiently in an alternating current circuit. A further object of the invention is to provide an improved power relay having means for effecting an abrupt shut-off of the arc which normally tends to continue when a circuit is broken. Other objects relate to various features of construction and arrangement which will appear more fully hereinafter.

The nature of the invention will be understood from the following specification taken with the accompanying drawings in which two embodiments of the invention are illustrated. In the drawings,

Figure 1 shows a rear elevation of one form of power relay embodying the present invention;

Fig. 2 shows a front elevation of the relay illustrated in Fig. 1;

Fig. 3 shows a bottom plan view of the relay illustrated in Figs. 1 and 2;

Fig. 4 shows a side elevation of the relay illustrated in Figs. 1 and 2, looking toward the left as viewed in Fig. 1;

Fig. 5 is a somewhat diagrammatic view of the circuit connections of a power relay embodying

the present invention, showing one use to which the relay may be put;

Fig. 6 is a perspective view of the magnetic core and magnetizing coil of the relay shown in Figs. 1 to 4, inclusive, with a portion of the bracket by which the armature is supported on the upper portion of the core broken away;

Fig. 7 is a perspective view of the armature which is actuated by the core illustrated in Fig. 6, together with the spring contacts which are operated by the movement of the armature;

Fig. 8 shows a top plan view of the shaft and spring by which the movement of the armature is controlled;

Fig. 9 shows a side elevation of the lever arm by which the tension of the spring connected to the armature shaft may be regulated;

Fig. 10 is a perspective view of one of the laminations of a shading coil employed in the pole face as shown in Fig. 6; and

Fig. 11 is a bottom plan view of a modified form of the invention in which magnetic blow-out coils are employed for preventing arcing of the contacts when the circuit is broken.

Before proceeding to a description of the construction of the improved power relay, reference will be made to the circuit connections of one possible use of the invention, as illustrated in Fig. 5. As there shown, two line conductors 15, leading from a source of alternating or direct current supply, are connected to movable contact members 16, each of which is adapted to engage either one of two stationary contacts 18 and 20. The contacts 16 are connected by conductors 20 to the terminals of a load 21, and the contacts 18 are connected by conductors 22 to the terminals of another load 23. By changing the positions of the movable contact members 16, either of the loads 21 or 23 may be connected in the circuit of the line conductors 15. This movement of the contact members 16 is effected by a magnetizable armature 24 which is adapted to be actuated by a magnetizable core 25. The winding of the core 25 is adapted to be energized by a current supplied thereto through conductors 26, leading from the secondary winding of a transformer 27 which has its primary winding connected through conductors 28 with a suitable alternating current supply. A switch 29 is connected in one of the conductors 26 which, for example, may be associated with the line conductors of a telephone circuit, the switch 29 being located at a point remote from the location of the relay which controls the contacts 16, 18, and 20.

As shown in Figs. 1, 2, 3, 4, and 6, the magnetizable core 25 of the relay is an E-shaped member, made up of superimposed iron laminations, secured together by rivets 25a, the core comprising parallel outer arms 25b and a central arm 25c upon which the magnetizing coil 30 is positioned. These arms 25b and 25c have pole faces 25d and 25e, respectively, the central arm 25c being adapted to be engaged by the armature 24 when the coil 30 is energized. The arms 25b are preferably slightly shorter than the arm 25c so that the central arm is the only one actually engaged by the armature, there being small air gaps between the pole faces 25d and the armature, an arrangement which is adapted to prevent chattering when the relay is in use. The coil 30 is provided with an insulating covering 30a and is wound on an insulating spool having heads 30b at its ends, the length of the coil being such that the central arm 25c of the core projects beyond the adjacent insulating head 30b of the spool, as shown particularly in Fig. 1. This projecting portion of the arm 25c of the core is provided with a pair of parallel slots 25f extending inwardly from the pole face 25e thereof, as shown in Fig. 6, and these slots are occupied by portions of the shading coils 31 which are shown as being made up of superimposed laminations 31a of copper or the like, thus forming continuous rings which surround the outer end portions of the central arm 25c of the core. These shading coils, due to currents induced therein by the magnetic flux, are adapted to produce magnetic fields opposed to those caused by the winding 30 in the outer portions of the central arm 25c of the core, thus causing the resultant magnetic flux in the outer portions of the central arm to be out of phase with the magnetic flux passing through the portion of the pole face which lies between the two shading coils, with the result that a continuous magnetization is maintained in some portion of the pole face when the coil 30 is energized by alternating current, so that the armature 24 will be attracted to the core as long as the current continues to pass through the coil 30. The laminations 31a of each shading coil may be secured together and the apertures 31b of the shading coils are adapted to be fitted closely by the projecting portions of the magnetic core so that the shading coils are thereby held firmly in position.

The core 25 is connected with a parallel insulating plate 33, of "Bakelite" or other suitable material, which is attached to the core at the lower end of the relay by an internally threaded sleeve 34, engaged at one end by a screw 35 passing through the insulating plate and at the other end by the threaded extremity of one of a series of studs 36 which pass through the core.

At the upper end of the core 25, the side arms 25b are connected with the insulating plate 33 by a metal bracket 37, which has the form shown particularly in Figs. 4 and 6. This bracket comprises a top plate 37a having depending therefrom a pair of flanges 37b which are secured to the insulating plate 33 by screws 38 engaging threaded apertures therein. The depending flanges 37b of the bracket are formed integrally with parallel transversely extending arms 37c, which have their extremities turned inwardly, as shown at 37d, to seat against the faces of the upper ends of the arms 25b of the core. These inturned extremities 37d are provided with threaded apertures which are engaged by the threaded portions of two of the studs 36 previously referred to.

The bracket 37 which thus connects the insulating plate 33 with the upper end of the core, also serves to support the armature 24 which, as shown in Figs. 4 and 7, is made up of a plurality of laminations 24a of magnetizable material having a metal plate 24b seated against the outer side thereof. A hinge bracket 40 seats against the inner edge of the stack of laminations 24a and this bracket is secured to the laminations and to the plate 24b by rivets 41. Between the arms 40a of the hinge bracket, there is positioned an insulating block 42 upon which are seated the movable contact members 16 which are in the form of flat leaf springs of bronze or the like, each carrying a pair of oppositely projecting contact lugs 16a and 16b at its lower extremity. The contact springs 16 diverge downwardly from each other and their upper ends are engaged on their outer sides by an insulating plate 43 on which is seated a metal plate 44. A pair of screws 45 extend through the plate 24b, through the laminations of the armature, through the bracket 40, through the insulating members 42 and 43, the upper ends of the spring contact arms 16 and through the plate 44 which has threaded apertures to receive the ends of the screws, as shown in Fig. 7, so that the upper ends of the contact springs 16 are mounted rigidly on the armature and are insulated therefrom.

The arms 40a of the bracket 40 extend on the inner sides of the arms 37c of the bracket 37 and are pivotally connected therewith by a shaft 47 which extends through aligning apertures in the ends of the arms 40a and in the adjacent portions of the arms 37c. This shaft 47 has wound thereon a coil spring 48, shown more particularly in Fig. 8, which has its middle part engaging apertures in the shaft and which has its opposite end portions wound in opposite directions in helical fashion about the shaft, the extremities of the spring terminating in arms 48a which are provided with transversely bent extremities 48b arranged to fit into apertures 40b, formed in the arms 40a of the bracket 40 by which the armature is carried. The shaft 47 is normally held against rotation and the spring 48 tends normally to move the armature 24 to its open or retracted position, as shown in Fig. 4. The extent of this opening movement may be limited by the engagement of the upper side of the armature with the edge of the top plate 37a of the bracket 37, but it may also be limited by the engagement of the contact lugs 16a with the stationary contacts as hereinafter more fully described. In order that the tension of the spring 48 may be adjusted to regulate the force which must be applied to overcome the spring when the armature is attracted to its core, means are provided for turning the shaft 47 in its bearings. For this purpose, one end of the shaft is connected to a crank arm 49 which is in the form of a flat plate adapted to seat against one of the side arms 37c of the bracket 37. This crank arm 49 has an aperture 40a in one end thereof which is provided with outwardly extending notches 49b, shown in Fig. 9, into which a portion of the metal of the shaft 47 enters when the end of the shaft is riveted over the face of the crank arm as shown in Fig. 8. This crank arm may be used for turning the shaft 47 to create the desired tension in the spring 48 and, when that has been accomplished, the arm 49 may be secured in adjusted position by a screw 50 which engages an aperture in the outer end of the arm and a threaded aperture in the 75

adjacent arm 37c of the supporting bracket. By this method of construction the armature 24 is caused to move about a pivotal axis which extends parallel to the row of pole faces formed on the ends of the arms of the core so that all parts of the armature have substantially the same amplitudes of movement as the armature moves from one extreme position to the other and, with suitable proportions of the parts, substantially equal forces of attraction may be caused to be exerted on the armature by the several pole faces.

The large cylindrical heads 36a of the studs 36 are adapted to seat against an upright support 5 or panel 51 of an instrument board or the like, and the relay is adapted to be secured to this panel by screws 52 which pass through the panel and engage the internally threaded sockets 36b of the heads 36a, the screws 52 being inserted 10 from the rear side of the panel. The heads 36a of the studs are provided with transverse slots 36c for engagement with a screw driver or the like during the operation of securing the insulating plate 33 to the core of the relay. Although 15 the relay may be mounted in various positions, it may preferably be located in an upright position such as that shown in Fig. 4, with the springs 16 extending substantially in a vertical plane so that dust will not collect materially on 20 the operating surfaces of the contacts. When 25 thus mounted on the panel 51, the insulating plate 33 is at the front of the assembly in a convenient position for connecting to the contacts 30 carried there by the various conductors of the circuit in which the relay is used, such as the conductors which have been shown by way of example in Fig. 5.

For the purpose of connecting the conductors 26 to the terminals of the coil 30 by which the magnetizable core 25 is energized, the plate 33 40 is provided at its upper end with a pair of metallic contact plates 54 and these are opposed on the inner side of the plate by metal terminal plates 55 to which the conductors 56 leading 45 from the terminals of the coil 30 are soldered or otherwise secured. The plates 54 and 55 of each pair are secured together by screws 57 and also by contact screws 58 by which the ends of the conductors 26 may be clamped against the faces 50 of the plate 54 to complete the electrical connections.

The line conductors 15 shown in Fig. 5 are adapted to be connected to contact plates 66 which are located on the face of the insulating plate 33 opposite other metal plates 61 which are located on the inner surface of the insulating plate. These terminal plates 61 are soldered or otherwise secured to conductors 62 which have their other ends soldered or otherwise attached to the contact springs 16 adjacent the free ends thereof. The plates 66 and 61 of each pair are secured together and to the plate 33 by screws 63 and also by contact screws 64 which are adapted to receive beneath their heads the 60 extremities of the conductors 15.

The contacts 18, shown in Fig. 5, are riveted or otherwise secured to the free ends of metal brackets 65 which have the angular form shown particularly in Fig. 3, each bracket having a portion 65a seated against the inner face of the plate 33 and connected by an outwardly inclined portion 65b with an extremity 65c which lies parallel to the portion 65a and to which the contact 18 is riveted or otherwise secured. A 70 contact plate 66 is located on the outer face of

the insulating plate 33 opposite the portion 65a of each bracket 65 and these plates 66 are secured to the portion 65 and to the plate 33 by a screw 67 and also by a contact screw 68 which are adapted to receive beneath them the extremities of the conductors 20 by which the contacts 18 are connected with the load 21. When the armature 24 is in its upper position as shown in Fig. 1 and Fig. 4, the contacts 18 are engaged by the contact lugs 16a carried by the contact member 16. The contact members 19 shown in Fig. 5 are carried by brackets 70 which have their inner ends 70a seated against the inner face of the plate 33 and which have inclined portions 70b connecting the portion 70a 15 with the extremities 70c upon which the contacts 19 are mounted in positions offset from the plate 33 and from the portions 65a of the bracket 65. Contact plates 71 are seated on the outer face of the plate 33 opposite the inner portions 70a of the brackets 70 and these parts are secured together and to the insulating plate 33 by screws 72 and also by contact screws 73, which clamp the ends of the conductors 22 in position, thus connecting the contacts 19 with the load 25 23, as shown in Fig. 5. By this method of construction, the terminal screws by which all of the conductors are connected to the relay are readily accessible on the front face of the insulating plate 33 while all of the movable parts of the device are concealed behind this plate.

When the relay as thus constructed is connected in the circuit, in the manner illustrated in Fig. 5, the closing of the switch 29 will energize the electromagnet so that the core 25 will 35 attract the armature 24 and draw it downwardly from the position shown in Fig. 4, thereby causing the movable contact springs 16 to be swung to a position wherein the contact lugs 16b carried by their extremities will engage the contacts 19 and thus connect the line conductors 15 with the load 23. While the winding 30 of the core 25 is thus energized, the shading coils 31 will cause a lag of the magnetic field in certain parts of the pole face of the core behind the field in another part so that there will be a continuous 45 attraction of the armature 24 over some part of its area during the entire time that the coil 30 is energized. When the switch 29 is opened, the spring 48 will at once cause the armature 24 to 50 rise to the position shown in Fig. 4, and during this movement the contact lugs 16a carried by the contact springs 16 will move into engagement with the contacts 18, thus connecting the conductors 15 with the load 21. The mounting 55 of the contact springs 16 is such that as its contact lugs engage or disengage either set of contacts 18 or 19, there will be a wiping contact of the surfaces of the metal so that a good electrical connection is established each time that a 60 contact is made. Although the extreme upper movement of the armature 24 is limited by the top plate 37a of the bracket 37, the engagement with the part 37a does not occur until after the desired contact has been established between the 65 members 16a and 18.

If desired, the relay of the present invention may be used with the magnetizing coil 30 connected in a direct current circuit, in which case 70 the shading coils 31 may be eliminated. It is desirable when using the relay to break circuits in which comparatively large circuits are passing, and particularly when the relay is being employed with the line conductors 15 connected in a direct current circuit, to provide means for ex- 75

tinguishing the arc which tends to form between the movable contacts and stationary contacts each time the circuit is broken, and for this purpose the relay may be modified as shown in Fig. 11 to include permanent magnets in conjunction with the brackets which carry one set of stationary contacts, so that a magnetic field is maintained which tends to oppose the passage of a current through the gap between separated contacts, thus causing the flow of current to be shut off abruptly when the contacts are separated. In this arrangement, as shown in Fig. 11, the magnetizable core 18 corresponds to the core 25 of the construction previously described, and the insulating plate 83 corresponds to the plate 33 of the first form of the invention. All parts of the two relays are otherwise identical in construction except that the brackets 85 of non-magnetic material, corresponding to the brackets 65 previously described, have the contact-carrying portions 85c connected by right angularly extending portions 85b with the parts 85a which lie in contact with the inner face of the insulating plate 83, thus accommodating permanent magnets 90 which are secured in the recesses of the brackets and preferably insulated therefrom by being coated with insulating varnish. Each magnet is thus mounted closely adjacent the gaps between two stationary contacts and the cooperating movable contact, so that a magnetic field is set up which extends across these gaps or through the region between the contacts in which the tendency for arcing may arise when the contacts are separated. The coating of varnish on the magnet serves to insulate the magnet from the circuit passing through the bracket, thereby overcoming any tendency for an arc to pass from the contacts to the surface of the magnet itself. The effect of this magnetic field is to distort the arc and increase the length of its proposed path

between opposed contacts so that the arc is abruptly extinguished.

Although two forms of the invention have been shown and described by way of illustration, it will be understood that it may be constructed in various other embodiments coming within the scope of the appended claim.

I claim:

A relay construction comprising a core, an insulating panel arranged on one side of said core, means including a plurality of supporting members attached to said insulating panel and engaging said core for retaining said insulating panel in spaced relationship with respect to said core, means including a plurality of studs extending through openings provided in said core and in threaded engagement with said supporting members for securing said insulating panel to said core, a supporting panel arranged on the opposite side of said core, means including additional studs extending through openings provided in said supporting panel and in threaded engagement with said first-mentioned studs for supporting said core and the parts carried thereby upon said supporting panel, a movable armature carried by said core, means including a winding associated with said core for controlling the position of said armature with respect to said core, a stationary contact carried by said insulating panel and arranged between said insulating panel and said core, a movable contact arranged between said insulating panel and said core and associated with said stationary contact, means including said armature for controlling the position of said movable contact with respect to said stationary contact, and terminals for said winding and said contacts carried by said insulating panel.
